Mathis, L.L.P.; Earl A. Bright, II[57] **CLAIM**

The ornamental design for a seat, as shown and described.

DESCRIPTIONFIG. 1 is a perspective view as seen from the front and upper
left of a first embodiment of a seat showing my new design;

FIG. 2 is a front elevational view thereof;

FIG. 3 is a left side elevational view thereof, the right side
is symmetrical;

FIG. 4 is a top plan view thereof; and,

FIG. 5 is a rear elevational view thereof.

The broken line showing of a seat member in FIGS. 1
through 5 is for environmental purposes only and forms no
part of the claimed design.**1 Claim, 3 Drawing Sheets*****FIG. 1******FIG. 2***
